JAMES E. SHRADER, OF EDGEWOOD, PENNSYLVANIA, ASSIGNOR TO WESTINGHOUSE ELECTRIC & MANUFACTURING COMPANY, A CORPORATION OF PENNSYLVANIA.

METHOD OF AND MEANS FOR TRANSLATING SOUND WAVES.

Application filed October 11, 1922. Serial No. 593,682.

My invention relates to telephone systems and apparatus and particularly to sound-wave translating device of an improved type.

5 In its broad aspect, an object of my invention is to provide a sound-wave translating device and a circuit arrangement therefor, whereby sound waves may be faithfully translated into correspondingly modulated 10 electrical energy without impairing the quality, tone and quantity of the translated energy.

More specifically, an object of my invention is to provide a translating device which 15 is operable in an atmosphere of air, which embodies no moving parts and which is further characterized by its simplicity of design, efficiency of operation and lack of complicated adjustments, the several parts of 20 which may be easily made by existing automatic machinery and may be readily assembled with a minimum expenditure of time and of money.

The ordinary sound-wave translating device known as a resistor microphone of the carbon capsule type embodies certain inherent undesirable features well known to those skilled in the art, as, for instance, the employment of a vibratory element which 25 tends not only to introduce distortion, but also to complicate the construction of the transmitter.

In carrying my invention into practice, I provide a sound-wave translating device 30 which is based upon the fact that the amount of ionization in an electrical discharge contained in a gaseous medium is determined by the pressure of the medium.

In one form of my invention, the translating device comprises a pair of spaced electrodes which are coated with a radioactive material emitting ionizing radiations and which are shunted by an energy source 40 impressing a potential thereacross of sufficient value to establish an ionization space current. A repeater device of the three-electrode type is operatively associated with the translating device to convert the variations 45 in the intensity of the ionization current with pressure into amplified electrical currents of similar wave form.

With these and other objects and applications in view, my invention further consists in the nature, the mode of operation and the 50 details of construction hereinafter described

and claimed and illustrated in the drawing, wherein:

Figure 1 is a diagrammatic view of one embodiment of my invention;

Fig. 2 is a similar view of a modification. 60

In one form of my invention, a sound-wave translating device 1 is operatively associated with a repeater amplifying device 2, the latter serving to amplify the effects 65 of the former, all as hereinafter more fully described.

The translating device 1 comprises a pair of spaced electrodes 3 and 4 which are disposed in a gaseous medium having a relatively low ionization voltage, as, for instance, air. Adjacent surfaces of the electrodes 3 and 4 are coated with a radio-active substance, 5, as, for instance, uranium, radium or thorium. Such substances are characterized by the fact that they are continuously emanating high-velocity electrical particles, which sometimes take the form of alpha particles. Since the ionization voltage of the medium containing the electrodes 3 and 4 is low in comparison with the velocity of the particles, the space intermediate 70 the two electrodes 3 and 4 is continuously in a state of ionization. The space intermediate the two electrodes 3 and 4 may be rendered conducting by impressing a source 75 6 of direct-current energy thereacross through conductors 7 and 8, respectively.

Since the amount of ionization, which is produced by the rapidly moving charges emanating from the radio-active coatings 5 80 varies directly with the pressure of the atmosphere enveloping the same, it is seen that the effect of impressed sound waves upon the space-current path intermediate the pair of electrodes 3 and 4 is to correspondingly vary the intensity of the ionizing currents traversing the same. The modulated currents traversing the circuit connecting the electrodes 3 and 4 may be impressed upon the input elements 9 and 11 85 of a repeater device 12 through a coupling transformer 13, the primary winding 14 of which may be included in the conductor 8 while the secondary winding 15 of which is connected to the input elements just mentioned. 95

A grid biasing condenser 16 having a negligible impedance to currents of sound-wave frequency is included in the grid circuit while a grid-leak resistor 17 is connected in 100 105 110

shunt relation to the grid and filament elements 9 and 11, in order to control the intensity of the negative charges which are accumulated on the grid 9 of the repeater device 12. The tube 12 is also provided with the customary plate 18 and plate-filament circuit 19, the latter including a source 21 of direct-current energy and a primary winding 22 of a coupling transformer 23. A secondary 10 winding 24 of the coupling transformer 23 may be connected to the input elements of an amplifying device (not shown) or other circuit arrangement employing such modulated energy.

15 When sound waves are impressed upon the space-current path between the electrodes 3 and 4, the number of collisions between the high-velocity particles emanating from the electrodes 3 and 4 and the molecules of the 20 gas contained in the space therebetween are correspondingly varied. Thus, the intensity of the ionizing currents traversing the space-current path is modulated in accordance with the pressure variations. The resulting 25 modulated alternating currents traversing the primary winding 14 of the transformer 13 are impressed upon the input elements 9 and 11 of the repeater device 12 to cause greatly amplified currents of corresponding 30 wave form to traverse the plate-filament circuit thereof. The amplified modulated currents traversing the latter circuit may then be impressed upon other amplifying means (not shown) through the coupling transformer 23, having a primary 22 and a secondary 24.

35 The arrangement shown in Fig. 2 is distinguished from that of Fig. 1 in the design of the discharge electrodes of the translating 40 device. In this figure, the electrodes 25 and 26 comprise a cylinder and a rod, respectively, with the latter disposed in the longitudinal axis of the former. As in Fig. 1,

adjacent surfaces are coated with the radioactive material 5. The operation of this 45 figure is the same as that of Fig. 1.

In operation, my apparatus provides a space-current path having a variable impedance resulting from differences in pressure at successive instants at any point in a propagated sound wave traversing the space between two electrodes in the presence of an ionizing means. It will be obvious, therefore, that the dimensions of the space included between the electrodes should preferably be small, in the direction of propagation of the sound, as compared with the shortest wave-length of the sound.

While I have shown and described a particular means for producing an ionizing stream, as by radio-active substance, it is apparent that other means are applicable to my invention, as by thermal means, or photo-electric means. Moreover, while I have described two specific embodiments of my invention for the purpose of illustrating its principles of operation, various changes and modifications may be made therein without departing from the spirit and scope of my invention. I desire, therefore, that only 70 such limitations shall be imposed thereon as are indicated by the appended claim or demanded by the prior art.

I claim as my invention:

A sound-wave translating device comprising 75 an electrical circuit including a space-current path between two radio-active electrodes in the air, and means for amplifying the variations in an electrical quantity in said circuit resulting from sound waves in 80 said space.

In testimony whereof, I have hereunto 85 subscribed my name this fourth day of October, 1922.

JAMES E. SHRADER.
